UNITED STATES PATENT OFFICE.

OSCAR ANDREW ELLIS, OF SAN FRANCISCO, CALIFORNIA, ASSIGNOR TO AXEL E. ELLIS,
OF BOSTON, MASSACHUSETTS.

ROCK AND ORE CRUSHING MILL.

Application filed October 9, 1917, Serial No. 195,628. Renewed July 14, 1923.

To all whom it may concern:

Be it known that I, OSCAR ANDREW ELLIS, a citizen of the United States, and a resident of the city and county of San Francisco, State of California, have invented certain new and useful Improvements in Rock and Ore Crushing Mills, of which the following is a specification.

The invention relates to crushing mills 10 and more particularly to mills of the ball type.

One of the leading objects of the invention is to provide a mill of this character from which all shafts, journals, bearings 15 and gearing have been eliminated, thereby reducing friction and wear to a minimum. Another object is to provide a mill which shall have improved crushing qualities and in which the balls are caused to rotate so 20 that they wear evenly in all directions, thus preserving their spherical shape. Another object is to so construct a mill of this character that the balls are free to ride over or around any piece of material too large or 25 too hard to be entirely crushed at the first impact. By virtue of this arrangement the necessity for breaking the material into exceedingly small lumps before feeding it to the mill is obviated.

30 A still further object is to improve the construction and proportion of the balls themselves, so as to secure greater efficiency as well as increased ease of transportation. Other advantages and improved details of 35 construction will appear from the following description.

In order that the invention may be clearly understood, reference is had to the accompanying drawings, forming a part of 40 this specification, and in which;

Fig. 1 is a side elevation of my improved mill, parts being broken away;

Fig. 2 is a plan view thereof with the saddle and associated parts removed;

Fig. 3 is a transverse vertical section substantially on the line A—B of Fig. 2;

Fig. 4 is a sectional elevation of one of the balls;

Fig. 5 is a fragmentary perspective view 50 of a portion of the lining of the trough or runway;

Fig. 6 is a fragmentary inverted plan view showing the bottom of such lining; and

Fig. 7 is a plan view on a reduced scale,

showing the method of transporting the balls by rolling them along the ground.

Referring to the drawings in detail, the mill is supported on a suitable base 3 of concrete, or the like, on which rests a floor 60 10, formed at one side to constitute a discharge trough, as shown in Fig. 2. Surrounding the floor 10 is a vertical retaining wall 9, which may be formed of wood or metal. 65

Seated on the foundation 3, inside of the wall 9, is an annular crushing trough or runway. This consists of a base plate 2, on which rests a suitable liner 17. As clearly shown in Figs. 1 and 2, the base 70 plate 2 is formed in sections, two of such sections being shown and being united at the joints 16 by means of internally and externally projecting radial flanges 14 and 11, respectively, through which pass suit- 75

The liner 17 is also preferably formed in sections and is secured in position on the bed plate 2 by means of bolts having tapering heads which seat in countersunk recesses 15, 80 adjacent the edges of the liner.

As both bed plate and liner are preferably made of heavy castings and may frequently have a more or less rough surface, it is very desirable to provide means for causing the 85 liner to seat firmly and solidly upon the base plate. This may be accomplished by placing a piece of canvas or the like between the liner and base plate, but, as shown, the preferred means consists in providing 90 on the bottom of the liner a series of chipping strips 18. Where any high places occur in the bed plate, this chipping strip may be removed by means of a cold chisel, or the like, and thus the irregularity compensated for. 95

A series of balls 1 are adapted to roll in the annular trough formed by the bed plate and lining. These balls are preferably made hollow so that they can be of relatively large size without being excessively heavy. Dia- 100 metrically opposed openings 22 are formed in these balls, and these openings are preferably lined with a malleable metal sleeve 23, so as to prevent chipping of the edges 105 of the openings. When in use, these openings are closed by means of screw-threaded plugs 24, terminating flush with the surface of the ball.

The primary object of the openings in the 110

balls is to permit a rod to be passed through such openings so that the balls may be rolled along the ground when transporting the mill from place to place. This is conventionally shown in Figure 7, in which 25 designates the rod passing through the openings in the ball and held at its ends in a suitable frame 26 to which a chain 27, or any other preferred haulage means, may be attached.

Resting freely upon the series of balls 1 is a saddle 4. This saddle is mounted without any shaft, or guiding or centering means whatsoever, and is capable of both vertical and lateral movement. The saddle is also preferably formed in sections connected by flanged joints 12 in a manner similar to the bed plate 2. In order to rotate the saddle, I provide a belt pulley 5 of relatively large size, the lower edge of which is secured to the top of the saddle, as clearly shown in Fig. 3. A belt 6, from any suitable source of power passes around the pulley 5 to drive the same.

Supported by the saddle, inside of the pulley, is a table or platform 21, on which suitable weights may be placed to give the desired crushing pressure to the balls. A feed hopper and chute 19 extend down through the middle of the pulley 5 and terminate at a point below the table 21, at the center of the annular runway.

Secured to the upper edge of the pulley 5 is a suitable bracket 13, which may have any one of a number of different shapes and which is designed to engage the trip arm or other operating part of any desired feed mechanism (not shown). It will be understood that as the pulley 5 revolves, this bracket 13 travels in a circular path and periodically actuates the feed mechanism, causing it to deliver the material to be ground into the chute 19.

Surrounding the base plate 2 is a circular flaring wall 7, which contains the usual screens 8 through which the ground material passes.

Referring particularly to Fig. 3, one of the most important features of the invention resides in the special shape given to the upper surface of the liner 17. From an inspection of the drawing, it will be seen that the curvature of the outer portion of this liner conforms closely to that of the balls 1, while on the inside the curve is much flatter, being preferably a plane surface substantially tangential to the curvature of the balls. The under-surface of the saddle 4 is preferably formed in the same way, the outer portion thereof being shaped to closely hug the balls, while the inner portion is flattened to a point approaching the tangential relation. The result of this special construction is first, that the balls being held by centrifugal force to the outside of

the trough or runway press closely against the outer side thereof and produce the finest crushing at this point. Secondly, the tangential surface of the runway forms with the balls an inwardly flaring throat adapted to receive the coarse material from the chute 19. Owing to the shape of the parts, it will be seen that the material works gradually outwardly and under the balls, becoming crushed more and more finely as it travels toward the outer periphery of the trough. The third important function of the special trough above described, is that it permits the balls to be laterally displaced and slightly deviated from their circular path in case an obstruction is encountered. This deviation is also made possible by the fact that the saddle runway is preferably shaped similar to the bed runway and by the further fact that both runways are relatively shallow, their edges terminating at points well removed from the plane of the ball centers. By virtue of this construction, the saddle is free to move laterally as well as vertically. A further result of the balls being thus deviated from their course is that they are thereby given a movement of rotation about a more or less vertical axis, thus shifting the position of the balls and causing them to continue their normal course with a different zone presented to the trough. In this way the balls are caused to wear equally in all directions and to preserve their spherical shape.

It will thus be seen that I have provided a ball mill in which both the balls and saddle are free to move laterally so as to ride over obstructions, while, at the same time, the design of the trough insures the material being ground to the finest condition at the point of discharge from the outer periphery thereof, and it is thought that the many advantages of my improved construction will be readily appreciated without further discussion.

What I claim is:

1. A crushing mill comprising an annular trough or runway, a series of balls rolling in said runway, the inner portion of said runway having a surface substantially tangential to that of the balls, and a saddle resting on said balls and held in position wholly thereby, said saddle being entirely free to move laterally in substantially all directions.

2. A crushing mill comprising an annular trough or runway, a series of balls rolling in said runway, the outer portion of said runway being of a curvature conforming substantially to that of the balls, and the inner portion of said runway being flattened into a curve of greater radius, and a saddle resting on said balls, said saddle being entirely free to move laterally in substantially all directions.

3. A crushing mill comprising a bed and a saddle, and a series of balls interposed between them, both said bed and saddle having an annular trough or runway in which such balls roll, a portion of the runway in both bed and saddle being of a curvature substantially conforming to that of the balls, and a portion being flattened into a surface approximately tangential to that of the balls, said saddle being free to move laterally in substantially all directions.

4. A crushing mill comprising an annular trough or runway, a series of balls rolling in said runway, the outer portion of said runway being of a curvature conforming substantially to that of the balls, and the inner portion being flattened into a surface approximately tangential to that of the balls, thereby permitting lateral displacement of the balls in said runway, and a saddle freely resting on said balls, in combination with means for rotating said saddle, such means comprising a belt pulley secured directly to and supported wholly by said saddle.

5. A crushing mill comprising a bed and a saddle, and a series of balls interposed between them, both said bed and saddle having a relatively shallow annular trough or runway in which said balls roll, the edges of said troughs terminating respectively well below and above the center of the balls, the outer portion of both the bed and saddle troughs or runways being of a curvature substantially conforming to that of the balls, and the inner portion of the bed runway being flattened into a surface approximately tangential to that of the balls, where-by said saddle and balls are capable of lateral displacement relative to the bed, and means for rotating said saddle, such means comprising a belt pulley secured directly and rigidly to said saddle.

6. A crushing mill comprising an annular trough or runway, a series of balls rolling in said runway, the outer portion of said runway being of a curvature conforming to that of the balls, and the inner portion of said runway being flattened into a curve of greater radius, and a saddle resting on said balls and controlled wholly thereby, said saddle being entirely unrestrained and free to move in all directions.

7. A crushing mill comprising a comparatively shallow trough or runway, a series of balls rolling in said runway, the middle and outer portions of said runway being of a curvature conforming to that of the balls, and the inner portion of said runway having a surface substantially tangential to the

curve of the middle and outer portions, and a saddle resting on said balls, said saddle being entirely unrestrained and free to move laterally except as controlled by the balls.

8. A crushing mill comprising a bed and a saddle, and a series of balls interposed between them, both said bed and saddle having an annular trough or runway in which such balls roll, the outer portion of the runway in both bed and saddle being of a curvature conforming to that of the balls, and the inner portion being flattened into a surface substantially tangential to the balls, said saddle being free to move laterally except as controlled by said balls.

9. A crushing mill comprising an annular trough, a series of balls rolling in said trough, a saddle resting on said balls, a belt pulley secured at its edge to said saddle, a platform supported by said saddle, said pulley and platform constituting a ballast chamber, and a feed chute extending down through said pulley, ballast chamber and platform and arranged to deliver material to be crushed at the center of said annular trough.

10. A crushing mill comprising an annular trough, a series of balls rolling in said trough, a saddle resting on said balls, a pulley attached at its edge to said saddle, a delivery chute extending down through said pulley, and an actuating device for feed mechanism carried by said pulley.

11. A crushing mill comprising an annular trough, a series of balls rolling in said trough, a saddle resting on said balls, a pulley attached at its edge to said saddle, a delivery chute extending down through said pulley, and an actuating device for feed mechanism comprising a bracket secured to the upper edge of said pulley.

12. The combination with a hollow cast-metal crushing ball having a pair of diametrically opposed openings therein, of a rod adapted to be passed through said openings to form an axis about which the ball may turn when being transported by rolling along the ground, and a pair of removable plugs adapted to close said openings when the ball is used for crushing, said plugs terminating substantially flush with the exterior of the ball, whereby a smooth crushing surface is provided.

In testimony whereof, I hereunto set my hand at San Francisco, California, this 29th day of September, A. D. 1917.

OSCAR ANDREW ELLIS.
